ECHO SUPPRESSOR

Charles Gillings, Liverpool, and Percy Edward Alexander Cowley, Coventry, England, assignors to Automatic Telephone & Electric Company Limited, Liverpool, England, a British company

Application September 15, 1943, Serial No. 502,548
In Great Britain November 14, 1942

3 Claims. (Cl. 178—44)

1

The present invention relates to echo suppressors for use in telecommunication systems, and is more particularly concerned with echo suppressors of the differential type which utilise variable attenuation networks connected in the "go" and "return" circuits respectively.

The invention is moreover particularly concerned with differential terminal echo suppressors in which it is known that lock-up trouble can occur if an outgoing signal is received over the 2-wire terminating circuit either prior to cessation of a signal incoming over the "return" circuit or during the hangover period of the echo suppressor after it has been biassed in the "return" direction. At the 4-wire/2-wire junction hybrid transformer in the echo suppressor the outgoing signal divides, part going into the "go" network where it is required and part into the incoming circuit from the "return" path. Under the above conditions that part of the outgoing signal which feeds into the incoming circuit may be sufficient to maintain the effect of the incoming signal after this has ceased so that the outgoing signal will continue to block its own "go" circuit for as long as it persists, the resultant lock-up effect being particularly serious under continuous tone signalling conditions. It is therefore the chief object of the invention to provide a simple and efficient means for overcoming the above-mentioned trouble by comparatively slight alterations to the circuit.

According to the invention, in a terminating differential echo suppressor of the type provided with variable attenuation networks in the go and return paths and arrangements for varying the attenuation of each network under the control of signal currents in the opposite path in which a signal incoming over the two-wire line at a time when the echo suppressor is biassed in favor of an incoming signal over the return path of the four wire line is prevented from maintaining this bias against itself by deriving the control current for producing increased attenuation in the go direction from the balancing resistance of a hybrid transformer in circuit with the return path amplifier.

The invention will be better understood from the following description of two methods of carrying it into effect, reference being had to the accompanying drawings comprising Figs. 1 and 2. Both of these solutions to the lock-up problem are assumed to be applied to a known form of differential terminal echo suppressor in which the variable attenuation networks are of the type employing dry rectifiers.

2

The principle is to prevent signals from the 2-wire line from entering the "go" amplifier signal rectifier which connects with the "return" circuit and which is normally actuated by signals from this circuit to produce high loss in the "go" circuit; at the same time the extension of signal energy from the "return" circuit to this rectifier must not be prevented.

In Fig. 1 the above-mentioned lock-up trouble is overcome by arranging for connection to the input side of the "go" amplifier signal rectifier to be taken from the terminating hybrid coil balance resistance, which will receive very little energy when signals are received over the 2-wire line with the result that only a small amount of energy will be communicated to the "go" amplifier signal rectifier. On the other hand, when a signal is communicated to the hybrid coil from the "return" circuit the signal energy is divided between the balance resistance and the 2-wire line so that the signal rectifier comes into operation to block the "go" circuit.

Fig. 1a shows schematically the bridge network in the echo suppressor from which the control currents for the variable attenuation networks in the "go" and "return" circuits are derived.

Fig. 2 shows the echo suppressor circuit in partial schematic form and modified by the use of an additional hybrid transformer for connecting the "return" circuit amplifier output to the terminating hybrid transformer and also to the input circuit of the "go" amplifier signal rectifier.

Referring now to Fig. 1, the "go" and "return" circuits are designated GO and RN respectively, while the 2-wire line is designated 2WL. RVAN and GVAN are the variable attenuation networks in the "return" and "go" circuits respectively, while RA and GA represent the "return" and "go" circuit amplifiers. The corresponding signal rectifiers are designated SRRA and SRGA, while H is the 4-wire/2-wire terminating hybrid transformer represented by its equivalent circuit.

With the echo suppressor in a quiescent state, a small control current is applied to each attenuation network from the D. C. bridge in the directions indicated by the arrows in Fig. 1a; this current finding a circuit to earth through the common high resistance YC. Under this condition the line series rectifiers in each attenuation network are biassed by the direct current flowing therethrough so that both networks are of low attenuation.

Assume now that an incoming A. C. signal is

received over the "return" circuit RN. This signal extends through network RVAN and is then amplified by amplifier RA and communicated to terminals *aa'* of the hybrid transformer H. On this hybrid transformer the balance resistance YD in conjunction with the parallel-connected impedance of the input circuit to the "go" amplifier signal rectifier SRGA is arranged approximately to match the impedance of the line 2WL when looking into the hybrid side of the transformer LT so that the amplified signal voltage appearing across terminals *aa'* will, in accordance with the well-known properties of the hybrid transformer, appear across terminals *ff'* and *ee'* but very little potential will appear across terminals *dd'* so that there will be practically no tendency to self-oscillation. That part of the amplified signal which appears across terminals *ee'*, is communicated to the line 2WL while the part appearing across resistance YD is communicated to the signal rectifier SRGA which in response thereto lowers the negative bias potential on the grid of the valve in the "go" amplifier GA. The effect is that this valve unbalances the bridge circuit of Fig. 1a with the result that an out-of-balance current will flow across the bridge through the networks RVAN and GVAN in the direction bottom to top in this figure. Network RVAN therefore remains at low loss while network GVAN will be of high loss due to the reversal of current flow therethrough. In this manner the echo-suppressor is biased in favour of the "return" circuit.

In the case of a signal received over the line 2WL and with the echo suppressor in quiescent condition, the signal energy is divided between *dd'* and *aa'* on the hybrid transformer H and very little alternating voltage appears across resistance YD. The alternating voltage appearing across *dd'* is communicated via network GVAN and thence via the "go" amplifier GA and the output transformer OT to the "go" line, a tertiary winding on this transformer communicating some of the energy into the "return" circuit amplifier signal rectifier SRRA. The bias on the grid of the valve in the amplifier RA is thereupon decreased, whereupon the bridge network is unbalanced in the opposite direction to that obtaining with a "return" signal so that the resultant control current is in such a direction as to render network GVAN of low loss and network RVAN of high loss. As regards the alternating voltage appearing across *aa'* of the transformer H, this causes an alternating signal current to be superimposed on the anode direct current flow of the valve in amplifier RA, but this is without effect as far as the RN line is concerned.

Considering now the case where the echo suppressor is biased in the "return" direction and a signal is received over the 2-wire line 2WL. When this signal is received there will be already a high loss in network GVAN so that it cannot be communicated to the "go" network. When the incoming signal over the "return" circuit ceases, the energy communicated to terminals *aa'* of the transformer H and from there to the terminals *ff'* will cease so that the bias on valve GA will restore to its normal value. The D. C. bridge network will then restore to a state of balance and both attenuation networks RVAN and GVAN will again become of low loss. The outgoing signal energy received over the 2-wire line will now take effect to bias the echo suppressor in the "go" direction as already described, it being appreciated that since very little of this

energy can be communicated to terminals *ff'* of transformer H and thence to the signal rectifier SRGA, it cannot possibly maintain the block on its own "go" circuit and so cause lock-up.

The success of the arrangement described depends ultimately on the correct balance of the anode circuit impedance of the amplifier RA with the impedance obtaining between the points *dd'*, and since this balance can be readily adjusted, the scheme is extremely attractive, as carrying it into effect involves no additional components.

Referring now to Fig. 2 in which an additional hybrid transformer SH is provided to suppress the flow of energy from the 2-wire line 2WL into its own signal rectifier SRGA, a signal received over the "return" circuit RN will produce an alternating voltage across terminals *aa'* of the suppressor hybrid SH, the signal energy then being divided in usual manner between the balance resistance YE together with the input circuit to the "go" amplifier signal rectifier SRGA and the output terminals *ee'* which connect with the input terminals *aa'* of the terminating hybrid transformer H. From terminals *aa'* of transformer H the signal energy is communicated to the line 2WL, while the energy delivered to the input of SRGA functions to bias the echo suppressor in favour of the "return" circuit in the manner already described for Fig. 1.

As regards a signal received over the line 2WL, part of this signal energy is delivered to the "go" network GVAN and part to the terminals *aa'* of transformer H in usual manner. That part which extends to the "go" network is extended to line via the "go" amplifier and the suppressor is biased in the "go" direction by virtue of the energy derived from the tertiary winding of the "go" amplifier output transformer. As regards the energy delivered to terminals *aa'* of transformer H, it is impossible for sufficient to be communicated back into the "go" amplifier signal rectifier SRGA to block its own circuit due to the fact that when it arrives at the suppressor hybrid transformer SH, the applied alternating voltage will appear only across terminals *aa'* and *dd'* in usual manner and only a negligible amount will be delivered to the balance resistance YE and associated connection to the input of SRGA. For this reason it is impossible for energy received over the 2-wire line to maintain the effect of a "return" signal which has just ceased, and so to block its own "go" circuit.

The correct functioning of this arrangement depends on maintaining a correct impedance balance of the anode circuit of the RA amplifier valve with the resistance YF, which balance can be accurately adjusted so that for potentials applied to terminals *ee'* in response to signals over the 2-wire line practically no voltage will appear across resistance YE and the connection to the input of SRGA.

It will be understood that the invention is not limited in application to the precise differential terminal echo suppressor circuit shown and described and that modifications or improvements may be made to this circuit without exceeding the scope of the present invention.

We claim:

1. For use in telecommunication systems a terminating differential echo suppressor comprising go and return paths, a variable attenuation network in each of the paths, a signal rectifier associated with each path for varying the attenuation of each network under the control of signal currents in the opposite path, a two-wire line, a

four wire/two wire hybrid transformer transferring signal currents from the return path to said two-wire line, means for deriving a signal current at one point in said circuit responsive to signal currents incoming over said two wire line, means for feeding said incoming signal currents to the go path, a balancing resistance associated with the hybrid transformer, and means connecting the input circuit of the signal rectifier of the go path across said balancing resistance to derive a control current from said balancing resistance to produce increased attenuation in the go path so as to prevent a signal incoming over the two wire line at a time when the echo suppressor is biased in favor of an incoming signal over the return path from maintaining this bias against itself.

2. For use in telecommunication systems, a terminating differential echo suppressor comprising go and return paths, a variable attenuation network in each of said paths, a signal rectifier associated with each path for varying the attenuation of each network under the control of signal currents in the opposite path, a two-wire line, a four-wire/two-wire hybrid transformer for transferring signal currents incoming over said two-wire line to said go path and for transferring signal currents outgoing from said return path to said two-wire line, a balancing resistance associated with said hybrid transformer and means connecting the input circuit of the signal rectifier of the go path across said balancing resistance to derive a control current from said balancing resistance to produce increased attenuation in the go path so as to prevent a signal incoming over the two-wire line at a time when the echo suppressor is biased in favor of an incoming signal over the return path from maintaining this bias against itself.

3. For use in telecommunication systems, a terminating differential echo suppressor comprising

5 go and return paths, a variable attenuation network in each of the paths, a signal rectifier associated with each path for varying the attenuation of each network under the control of signal currents in the opposite path, a two-wire line, a first four-wire/two-wire hybrid transformer for transferring signal currents incoming over said two-wire line to said go path and for transferring signal currents outgoing from said return path to said two-wire line, a second four-wire/two-wire hybrid transformer connected between said return path and said first hybrid transformer, a balancing resistance associated with said second hybrid transformer and means connecting the input circuit of the signal rectifier of the go path across said balancing resistance to derive a control current from said balancing resistance to produce increased attenuation in the go path so as to prevent a signal incoming over the two-wire line at a time when the echo suppressor is biased in favor of an incoming signal over the return path from maintaining this bias against itself.
